ATTORNEY

UNITED STATES PATENT OFFICE.

GRACE ROBARTS, OF NEW YORK, N. Y.

DESIGN FOR A BONBON-LIFTER.

SPECIFICATION forming part of Design No. 26,726, dated March 9, 1897.

Application filed January 25, 1897. Serial No. 620,700. Term of patent 7 years.

To all whom it may concern:

Be it known that I, GRACE ROBARTS, a subject of Her Majesty the Queen of Great Britain, residing at the city of New York, in the county and State of New York, have invented and produced a new and original Design for a Bonbon-Lifter, of which the following is a specification, reference being had to the accompanying drawings, forming part thereof, and in which—

Figure 1 is a side elevation of a lifter bearing and incorporating my design, and Fig. 2 is an enlarged vertical section of same on the dotted line 2 2 of Fig. 1.

15 The leading features of my design pertain more particularly to the blade of the instrument, and consist in the blade having its lower edge substantially straight and its upper edge adjacent to its point provided with a triangular-shaped projection, which in use will enter the bonbon or other article and retain the same upon the blade, substantially as illustrated in the accompanying drawings.

20 In the drawings, A designates the blade of the lifter, and B a suitable handle therefor.

The lower edge C of the blade A is substantially straight, and the upper edge of the blade adjacent to its pointed end has the triangular elevation or projection D of a height not too great to enable it to enter a bonbon, 30 cherry, or like article and to retain the same while the latter is being lifted to the mouth.

In the drawings I show an additional and larger projection E on the blade A to indicate that when the lifter is to be adapted for fairly 35 large as well as small bonbons or other articles the extra projection E will be used, the blade then piercing the article until both projections D E are embedded therein.

What I claim is—

40 The design for a lifter for bonbons and like articles, substantially as shown and described.

Signed at New York, in the county and State of New York, this 22d day of January, 1897. 45

GRACE ROBARTS.
